UNITED STATES PATENT OFFICE

117,043

DESIGN FOR A COOKY

Josephine Huber, Elmwood Park, Ill.

Application June 30, 1939, Serial No. 85,775

Term of patent 14 years

To all whom it may concern:

Be it known that I, Josephine Huber, a citizen of the German Reich, residing at Elmwood Park, in the county of Cook and State of Illinois, have invented a new, original, and ornamental Design for a Cooky, of which the following is a specification, reference being had to the accompanying drawing, forming a part thereof.

I claim:

The ornamental design for a cooky, substantially as shown.

JOSEPHINE HUBER.
